UNITED STATES PATENT OFFICE

GEORGE F. BORKMAN, OF SALT LAKE CITY, UTAH

BALANCED RESILIENCY MULTIPLE-ACTION ONE-PIECE DIAPHRAGM

Application filed March 31, 1926. Serial No. 98,937.

This invention relates to a balanced resiliency multiple action one-piece diaphragm, for the production or reproduction of sound, and its principal objects are:

5 First. To provide a diaphragm which may be used for sending or receiving, that is, for use either with a microphone or with a telephone or radio receiver.

Second. To provide a diaphragm which 10 shall have balanced resiliency, thereby avoiding the necessity of the customary polarity selection when assembling and testing the instruments in which the diaphragms are used.

Third. To obtain in a single diaphragm a 15 high degree of tone variation, with equal fidelity to pitch whether the tone vibrations are of high frequency or low frequency.

Fourth. To obtain in a thin sheet diaphragm the advantages sought by others in 20 a heavy rim and light center construction, these latter having been found to be costly and impractical, especially where attempts have been made to build up the diaphragms of mica in laminated form.

25 Fifth. To confine the major effect of sound vibrations to the central portion of the diaphragm.

Sixth. To cause the light tone impulses to affect the central portion of the diaphragm 30 and to automatically cause the stronger tone impulses to act upon the outer portion of the diaphragm when the center portion becomes overloaded.

Seventh. To obtain high quality of manufacture at a minimum cost.

Eighth. To adapt the construction of the diaphragm to modern methods of quantity production.

Ninth. To combine in an instrument with 40 one diaphragm the effects usually obtained only by two or more instruments playing at one time, in close proximity to each other in order to obtain the reproduction of high and low notes, either vocal or instrumental, there- 45 by achieving a result which is being largely sought at this time by all persons interested in sound reproduction.

These objects are attained preferably by stamping the diaphragms from thin sheet 50 metals such as aluminum, and providing a se-

ries of corrugations concentric with the diaphragm, and in addition, a series of radial corrugations which may intersect the concentric corrugations. The radial corrugations are spaced equally around the center of the diaphragm, and extend inwardly, preferably from the circumference of the diaphragm, to an extent depending upon the relation of the tone qualities to be borne by the central portion of the diaphragm in comparison with the outer portion thereof.

The radial corrugations further, are formed in alternating relation to each other, that is to say, one corrugation shall be concave when considered from one surface of the diaphragm, while the next corrugation shall be convex when considered from the same surface. Thus, there are an even number of radial corrugations. The diaphragm may be mounted in any customary way and may be connected to an actuating armature by the usual pin or link.

The features of this invention for which the protection of Letters Patent is desired, are collectively grouped in the claims concluding this specification.

In the drawing,

Fig. 1 represents the plan of a diaphragm constructed in accordance with this invention;

Fig. 2, a section on line 2 in Fig. 1;

Fig. 3, a developed section on line 3 in Fig. 1;

Fig. 4, a plan showing a modification; and

Fig. 5, a section on line 5 in Fig. 4.

Referring to the drawing, the diaphragm 10 has the usual clamping margin 12 by which it is held in place in its mounting. At the center of the diaphragm is the cup portion 14 which is preferably in the form of the hollow frustum of a cone. Concentric with the frustum are the corrugations 15 to 21, these corrugations being consecutively adjacent each other and occupying the area between the base of the frustum and the clamping margin 12. Extending radially across the corrugations 18 to 21 are the convex corrugations 24 alternating with the concave corrugations 25, the terms convex and concave being used in this instance, relatively to the

top surface of the diaphragm, as shown in Figs. 1 and 3.

The diaphragm 34 in Fig. 4, has the cup 26 and the convex radial corrugations 31 alternating with the concave radial corrugations 32.

The relative differences in the shapes of the cups 14 and 26 and the differences in the arrangements of the concentric corrugations 15 to 21 and 27 to 30 represent the facility 10 with which differences in tone pitches of various diaphragms may be effected.

The diaphragm represented in Fig. 1 is typical of the general arrangement for producing tones of low pitch, for the reason that the sound impulses would affect the diaphragm largely within the central portion thereof. On the other hand, the frustroconical cup represented in Fig. 4 having a 20 much larger base than the cup 14 in Fig. 1, would bring the effect of the sound impulses nearer to the margin thereof.

By properly proportioning and arranging the cup and the concentric corrugations, and 25 then by properly placing the radial corrugations, almost any desired tonal qualities can be provided for in a single diaphragm.

In ordinary diaphragms, that is those not having my alternating convex and concave 30 radial corrugations, the tone action of the diaphragm when moved in one direction, is different from the tone action when the same diaphragm is moved in the opposite direction, this being probably due to an unavoidable 35 difference in the two surface structures of any sheet of material.

I have found, as the result of many experiments, that the alternating arrangement 40 of the radial corrugations as herein disclosed, overcomes this undesirable condition present in ordinary diaphragms, thus making unnecessary in my improved construction, the polarity selection of the diaphragm.

While a typical embodiment of this invention is herein shown and described, it should 45 be clearly understood that all the detailed parts thereof, may or may not, appear in the preferred forms, and also, that the preferred forms may be varied from time to time, depending upon the circumstances and conditions governing and governed by, the development of this invention and the arts to which it is incident, therefore the scope of 50 this invention may be ascertained from the 55 claims in which its spirit is generalized.

Having fully described my invention, what I claim is:

1. A diaphragm substantially circular in 60 form and constructed of material of uniform thickness, said diaphragm comprising a centrally disposed cup portion, concentric corrugations surrounding the said cup portion in spaced relation to each other, and a plurality of radial corrugations spaced apart 65 from each other, the radial corrugations in-

tersecting a predetermined number of the said concentric corrugations, and being alternately concave and convex relatively to each other.

2. A diaphragm having a series of radial 70 corrugations formed therein in alternating convex and concave relation, and a second series of corrugations having individual member corrugations intersecting individual member corrugations of the said first series, 75 transversely with respect to the plane of the diaphragm.

3. A diaphragm of substantially uniform thickness having a plurality of radial corrugations formed therein, the lengths and 80 shapes of the said corrugations being similar to one another, but alternately concave and convex with respect to the plane of the diaphragm and a second series of corrugations having individual member corrugations intersecting individual member corrugations of the said first series, 85 transversely with respect to the plane of the diaphragm.

4. A diaphragm having a plurality of corrugations formed therein, said plurality comprising an even number of corrugations, one-half of which are concave and the other half convex, and a second series of corrugations having individual member corrugations intersecting individual member corrugations 95 of the said first series, transversely with respect to the plane of the diaphragm.

In testimony whereof I sign my name hereto.

GEORGE F. BORKMAN. 100
